CHARLES T. BRENNAN, OF WATERBURY, CONNECTICUT

CUT-OFF MECHANISM FOR HEADING MACHINES

Application filed May 27, 1931. Serial No. 540,266.

This invention relates to the cut-off mechanisms of metal heading machines of the type in which a rod, either hot or cold, is entered and sections cut off and carried into line with and compressed by a punch and die having complementary recesses that shape the cut pieces of rod into form, and as it is particularly adapted for machines for making metal balls, small or large, it is herein described as designed for forming balls.

In the prior machines of this class when the fed section of the rod is severed the transverse shearing movement of the cutter leaves the cut end somewhat rounded, or, if not rounded, oblique to the axis of the cut piece, owing to the drawing of the metal as it is sheared. As a result of this deformation of the blanks, which is particularly marked when hot rod is used, the blanks do not line accurately with and enter the semi-spherical cavities of the ball forming punch and die uniformly, and consequently when the punch and die come together the balls are not shaped perfectly spherical, or if spherical are more dense at one sector than another, and furthermore such irregularity of the blanks causes excessive wear on the walls of the punch and die cavities.

The object of the present invention is to provide means for machines of this nature, which will cut blanks from hot or cold rod in such manner that the ends will be square and in planes at right angles to the axes of the blanks, and which will carry these blanks into exact axial alignment with the semi-spherical cavities in the punch and die, so that when the punch compresses the metal into the die, balls will be formed that are not only spherical but of equal density throughout.

This is accomplished in the illustrated embodiment of the invention by arranging opposite the slide which carries the blade that cuts the stock from the rod, a slide with a blade that backs the rod, particularly at the cut edge, so that the section being severed will be closely confined by the blades and cannot be deformed when the cut is made, the actuating mechanisms of the slides being so

controlled and co-related in their movements that this is easily and smoothly effected.

Fig. 1 of the accompanying drawings shows a plan of the improved cut-off mechanism applied to a well known type of metal heading machine. Fig. 2 shows a vertical transverse section on the plane indicated by the dotted line 2—2 on Fig. 1. Fig. 3 is a view looking at one side of the machine and showing the backing slide operating mechanism. Fig. 4 is a horizontal section on larger scale showing the relations of the punch and die and the cut-off mechanisms in the positions occupied when a piece of rod is about to be cut. Fig. 5 is a similar view with these elements related as when a ball is formed. Fig. 6 is a horizontal section showing the backing slide controlling elements in one position. Fig. 7 is a similar view showing the backing slide controlling elements in another position.

In the views only so much of the frame 1 of a heading machine of well known type as is necessary to an understanding of the invention, is illustrated. In a bracket 2 on one side of the frame is a slide 3 that is reciprocated by a link 4 connected with a crank pin 5. This slide has a cam groove 6 formed by hardened inset pieces 7 in which lies a roll 8 that is connected with the cutter bar 9. For the purpose of adjustment the roll 8 is mounted on a block 10 that is held in a slot 11 in the cutter bar by a screw 12. Fastened to the inner end of the cutter bar is the cutting blade 13. Fastened to the outer end of the cutter bar is a lug 14 through which extends a screw 15 that has nuts 16 adjustable to limit the outward movement of the cutter bar, Fig. 2.

By this mechanism when the cutter slide is moved forward the cutter is moved inward across the end of the hardened bushing 17 through which the rod of stock 18 is fed, and severs the section which forms the blank and carries it into line with the push 19 and die 20. This cut-off mechanism is of conventional design.

On the opposite side of the frame in a bracket 21 is a slide 22. This slide is connected by a link 23 with a yoke 24 that has a roll 25 engaged in a cam groove 26 in the cam disk 27 on the main shaft 28, Figs. 1, 2, 304

Fixed on this slide is a cam block 29 and hinged on the slide by pin 30 is a plate 31 that has a cam block 32.

The free end of the plate 31 has a roller 33 which runs in contact with a cam bar 34 that is hinged at 35 to the supporting bracket 21. The cam bar 34 is held in engagement with the roller 33 by a plunger 36 that is pressed inward by a strong leaf spring 37 which is fastened to an arm 38 secured to the side of the bracket.

Opposite the cutter 13 is the backing blade 40 that is fastened to the inner end of the backing bar 41. Adjustably held in a slot 42 in the backing bar, by a screw 43, is a block 44 which carries a roll 45 that lies in the oblique slot 46 formed by the fixed cam 29 and hinged cam 32. By this mechanism when the slide 22 is drawn backward the backing blade 40 is forced inward toward the cutter blade, and when the slide is moved forward the backing blade is drawn outward. At the outer end of the backing bar is a lug 47 and screw 48 for limiting the inward movement 25 of the backing bar.

Immediately a length of rod is fed through the feed bushing 17 the cutter blade 13 moves inward against one side of the projecting end of the rod and the backing blade 40 moves 30 inward against the other side so the rod is gripped between the blades. The cutter blade continues its inward movement and the movement of the backing blade is reversed and the projecting end of the rod thus tightly gripped is carried across the feed bushing and a blank cut off. A continuation of this latter travel of the blades carries the blank into line with the punch and die, and as the punch closes the movement of the cutter 35 blade is reversed while the outward movement of the backing blade continues, so as to avoid the punch.

The backing slide has a longer travel than the cutter slide and the timing is such that 45 the backing blade moves inward toward the cutter blade faster than the cutter blade moves inward, but the cam mechanism for moving the backing slide tends to give the backing blade a slower outward movement 50 than the inward movement of the cutter slide as they move together for cutting and carrying the blank to the punch and die, so that the blank will be closely confined between the blades. This is possible due to the fact that 55 the cam surface 32 that moves the backing blade inward and controls its outward movement, is mounted on the hinged plate 31 that has the roll 33 engaged by the cam bar 34 which is pressed inward by the spring plunger 36. In other words, the positive mechanism tends to give the backing blade too much inward movement and too slow outward movement, in order to ensure a tight clamping of the blank between the blades, 60 which action is possible owing to the yielding 65

cams. By the provision of the yielding cam members the grip on the blank is tight and the required movements of the backing slide 22 may be controlled by a cam 26 on the main shaft 28 that has an easy action. This renders it unnecessary to synchronize the backing slide cam with the crank which operates the cutter slide.

After the punch has been retracted, the ball which is formed is freed from the die cavity 75 by the ejector pin 49 and is freed from the punch cavity by the ejector pin 50, which are actuated in the manner usual in machines of the type to which this cut-off is applied.

By the cut-off mechanism described the blanks are cut with square ends and are accurately carried into axial line with the cavities of the punch and die so that substantially perfect spheres of uniform density are produced with a minimum wear on the punch 80 and die and the several cams which actuate the slides.

The invention claimed is:

1. A cut-off mechanism for metal heading machines which have bushings through which the stock is fed and punches and dies for shaping the stock, said mechanism comprising a cutter blade and a backing blade, a slide with a cam for reciprocating the cutter blade across the feed bushing and toward and from axial line with the punch and die, and a slide with a yielding cam for reciprocating the backing blade across the axial line of the punch and die and toward and from the axial line of the feed bushing, said cams causing the blades to come together with a yielding pressure opposite the feed bushing, move together from said bushing toward the axial line of the punch and die and then separate.

2. A cut-off mechanism for metal heading machines which have bushings through which the stock is fed and punches and dies for shaping the stock, said mechanism comprising a cutter blade and a backing blade, a slide with a positive cam for reciprocating the cutter blade across the feed bushing and toward and from axial line with the punch and die, and a slide with positive and yielding cams for reciprocating the backing blade across the axial line of the punch and die and toward and from the axial line of the feed bushing, said blade reciprocating mechanisms causing the blades to come together opposite the feed bushing, move together from said bushing toward the axial line of the punch and die and then separate.

3. A cut-off mechanism for metal heading machines which have bushings through which the stock is fed and punches and dies for shaping the stock, said mechanism comprising a cutter blade and a backing blade, a slide with a cam for reciprocating the cutter blade across the feed bushing and toward and from axial line with the punch and die, a

slide with a hinged cam for reciprocating the backing blade across the axial line of the punch and die and toward and from the axial line of the feed bushing, and spring means 5 for pressing said hinged cam inward, said cams causing the blades to come together with a yielding pressure opposite the feed bushing, move together from said bushing toward the axial line of the punch and die and 10 then separate.

4. A cut-off mechanism for metal heading machines which have bushings through which the stock is fed and punches and dies for shaping the stock, said mechanism comprising 15 a cutter blade and a backing blade, a slide with a positive cam for moving the cutter blade across the feed bushing and toward and from axial line with the punch and die, a crank for reciprocating the cutter slide, a slide with positive and yielding cams for moving the backing blade across the axial line of the punch and die and toward and from the axial line of the feed bushing, and a cam for reciprocating the backing slide, 20 said blade reciprocating mechanisms causing the blades to come together opposite the feed bushing, move together from said bushing toward the axial line of the punch and die and then separate.

5. A cut-off mechanism for metal heading machines which have bushings through which the stock is fed and punches and dies for shaping the stock, said mechanism comprising a cutter blade and a backing blade, mechanism 25 for reciprocating the cutter blade across the feed bushing and toward and from axial line with the punch and die, and mechanism for reciprocating the backing blade across the axial line of the punch and die 30 and toward and from the axial line of the feed bushing, said backing blade reciprocating mechanism comprising a slide carrying a fixed cam and a hinged cam, and spring means for controlling the action of the hinged 45 cam.

6. A cut-off mechanism for metal heading machines which have bushings through which the stock is fed and punches and dies for shaping the stock, said mechanism comprising 50 a cutter blade and a backing blade, mechanism for reciprocating the cutter blade across the feed bushing and toward and from axial line with the punch and die, and mechanism for reciprocating the backing blade 55 across the axial line of the punch and die and toward and from the axial line of the feed bushing, said backing blade reciprocating mechanism comprising a slide, a cam for reciprocating said slide, a cam fixed to said slide, a plate with a cam hinged to said slide, a roll mounted on said plate, a cam bar engaged with said roll, and a spring pressed 60 plunger engaged with said cam bar.

7. A cut-off mechanism for metal heading 65 machines comprising a cutter blade and a

backing blade, a slide with a cam for reciprocating the cutter blade, and a slide with a fixed cam and a yielding cam for reciprocating the backing blade.

8. A cut-off mechanism for metal heading machines which have bushings through which the stock is fed and punches and dies for shaping the stock, said mechanism comprising a cutter blade and a backing blade, a cam slide for reciprocating the cutter blade across 70 the feed bushing and toward and from axial line with the punch and die, and a slide bearing a yielding cam for pushing the backing blade inwardly across the axial line of the punch and die and toward the axial line of 75 the feed bushing, said slide also bearing a fixed cam for pulling the backing blade outwardly.

9. A cut-off mechanism for metal heading machines which have bushings through which the stock is fed and punches and dies for shaping the stock, said mechanism comprising a cutter blade and a backing blade, mechanism 80 for reciprocating the cutter blade across the feed bushing and toward and from axial line with the punch and die, and mechanism for reciprocating the backing blade across the axial line of the punch and die and toward and from the axial line of the feed bushing, said backing blade reciprocating 85 mechanism comprising a slide with a cam fixed thereto and a cam hinged thereon, a hinged cam bar, and spring means adapted to hold said cam bar in cooperative engagement with said hinged cam. 90
